UNITED STATES PATENT OFFICE.

JOHN W. ANDERSON, OF AURORA, ILLINOIS, ASSIGNOR OF ONE-HALF TO JAMES A. GRAHAM AND ELLA H. GRAHAM, BOTH OF AURORA, ILLINOIS.

TOILET OR VANITY CASE.

Application filed December 17, 1927. Serial No. 240,718.

This invention relates to improvements in toilet or vanity cases particularly adapted, though not necessarily limited in its use, for attachment to the outside of a purse or 5 hand bag where it will be convenient and readily accessible, thereby not only obviating the necessity of opening the bag when the case is to be used, but also the necessity of placing the case within the bag where it will become 10 married or where it will often open to spill some of the contents thereof within the bag.

A further object is to provide an improved vanity case of this character embodying two sections hingedly connected together, one of 15 the sections having a flap or member hinged to the free edge thereof and adapted to be folded between the case sections as a closure for one of the sections and as a protector for the contents of the other section, the said flap 20 being adapted to be unfolded outwardly to form a protecting shield to protect the garments of the user when the case is open and is in use.

To the attainment of these ends and the 25 accomplishment of other new and useful objects as will appear, the invention consists in the features of novelty in substantially the construction, combination and arrangement of the several parts hereinafter more fully 30 described and claimed and shown in the accompanying drawings illustrating this invention, and in which

Figure 1 is a perspective view of a hand bag having applied to the outside thereof a 35 case of this character constructed in accordance with the principles of this invention.

Figure 2 is a view similar to Figure 1, showing the case partly open.

Figure 3 is a view similar to Figure 2, 40 showing the case further opened and the protecting shield extending beyond the case.

Figure 4 is a detail sectional view taken on line 4—4, Figure 1.

Figure 5 is a detail perspective view of the 45 vanity case closed and detached from the bag.

Referring more particularly to the drawings the numerals 10 and 11 indicate two sections of a case which may be of any desired size and configuration and constructed of any 50 suitable material, preferably metal. These sections are hingedly connected together along one edge as at 12 and the section 11 is preferably shaped to form an open compartment 13, the wall 14 of which, adjacent the

hinge 12, is shaped so as to form a cup shaped 55 portion along the lower edge thereof, for a purpose to be set forth.

Within the compartment 13 may be arranged open chambers 15—16 of any size and configuration adapted to hold cosmetics and 60 also powder puffs 17—18. Other toilet articles 19 may also be arranged within the compartment 13.

The section 10 is provided with an up- 65 standing wall 20, and the walls of the compartment 13, when the sections 10 and 11, are closed with respect to each other, are adapted to telescope one with the other. Supported by the inside of the section 10 is a mirror 21 which may be placed in position and held 70 there in any suitable manner, and the mirror 21 is preferably of a size substantially equal to the area of the portion of the section 10 within the surrounding wall 20.

Connected with the free edge of the section 75 11, preferably by means of a hinge 22, is a flap or member 23 constructed of any suitable material, preferably metal and is of a size and configuration to be folded over the compartment 13 to form a closure therefor. The 80 free edge 24 of the member 23 is adapted to engage over the wall 14 of the section 11 so that the sections 10 and 11 may be folded close with respect to each other. The member 23 forming a closure for the compartment 13 85 will be folded between the sections 10 and 11 when the latter are closed, and the member 13 will also serve as a shield or protector for the mirror 21.

The cup shaped portion 14 formed along 90 the edge of the member 11 forms a pocket into which the articles 19 will drop when the section 11 is folded with respect to the section 10.

Any suitable fastening means, such as a 95 separable clip 25 may be provided for securing the sections 10 and 11 in a closed position.

With this improved construction it will 100 be manifest that the section 11 with the closure 23 in position thereover, as shown in Figure 2, may be opened so as to permit access to the mirror 21 and at the same time prevent the articles in the compartment 13 from falling out. The member 23 may be unfolded with respect to the section 11 so as to 105 project beyond the free edge of the section 11 to form a shield or protector for the gar-

ments of the person when the case is being used, as surplus powder or cosmetics will fall upon the shield 23 to be prevented from falling upon the garments of the user.

- 5 The case is adapted to be secured to the outside of a hand bag or purse 26, and any suitable means may be provided to accomplish that end. A simple and efficient means embodies a flange 27 which extends about the 10 edge of one of the sections, preferably the section 10, and is provided with apertures 28 by means of which the device may be secured by suitable fastening devices 29 or stitches to the outer face of the bag.
- 15 When secured to the bag as shown, access may be readily had to the interior of the case without necessitating the opening of the bag and the bag may itself be employed without interfering with the case.
- 20 If desired the case may be used independently of the bag, that is the flange 27 may be omitted or may be employed, but the case may be maintained free of and detached from the bag and may be carried in the hand or 25 placed in a pocket when desired.

While the preferred form of the invention has been herein shown and described, it is to be understood that various changes may be made in the details of construction and in the 30 combination and arrangement of the several parts, within the scope of the claims, without departing from the spirit of this invention.

What is claimed as new is:—

1. A toilet case embodying two sections

hingedly connected at one edge, a mirror arranged inside of one of said sections, the other of the sections being shaped to form a container for toilet articles, a partition hingedly connected with the free edge of the last said section and foldable thereover to 40 form a closure therefor, the free edge of said partition being deflected laterally with respect to the body thereof to engage over the hinged edge of the container section, said partition forming when unfolded, a ledge or 45 shield projecting from the container section with the deflected edge thereof uppermost said shield being adapted when in a position to form a closure for the container section, to be folded between the said sections. 50

2. In combination a hand bag or purse and a toilet case secured to the outside thereof, said case embodying two sections hingedly connected together, means securing one of the sections to the bag, a mirror disposed within the case and carried by one of said sections, the other section being shaped to form a holder for toilet articles, and a closure hingedly connected to the last said section, said closure being foldable between the sections and 55 also adapted to be extended beyond the section to which it is connected to form a protecting shield when the case is in use. 60

In testimony whereof I have signed my name to this specification on this 14th day of 65 December, A. D. 1927.

JOHN W. ANDERSON.
